UNITED STATES PATENT OFFICE.

FREDERICK JOHN STAVELEY BULFORD, OF MAIDENHEAD, ENGLAND.

ARTIFICIAL LIMB.

1,345,661.

Specification of Letters Patent. Patented July 6, 1920.

Application filed August 29, 1919. Serial No. 320,591.

To all whom it may concern:

Be it known that I, FREDERICK JOHN STAVELEY BULFORD, of 74 High street, Maidenhead, in the county of Berks, Eng-
5 land, manager, have invented certain new and useful improvements in or Relating to Artificial Limbs, of which the following is a specification.

This invention relates to artificial limbs and has for its object to provide an improved form of peg leg which shall be lighter and cheaper than the usual forms of artificial legs. A further object of my invention is to provide a peg leg with means 15 simulating the shape of a human leg and foot.

According to this invention an artificial leg is provided with an annular support for the stump of the leg connected by a cage-like frame with a tubular peg and with a bucket depending from the annular support.

An artificial leg constructed in accordance with this invention may be modified for cases where the leg has been amputated 25 above or below the knee and it may, if desired, be articulated when intended for use in a case where amputation was made above the knee.

The invention is illustrated in the accompanying drawings wherein Figure 1 is a side elevation and Fig. 2 is a front elevation of one form of artificial leg. Fig. 3 is a side elevation and Fig. 4 is a front elevation of another form of artificial leg together with 35 means for securing it to the body of the wearer, Fig. 5 is a sectional side elevation of a detail on an enlarged scale and Fig. 6 is an elevation of another detail also on an enlarged scale. Fig. 7 is a front elevation, 40 partly in section showing the knee joint and associated parts on an enlarged scale and Fig. 8 is a side elevation thereof, partly in section.

The form of leg shown in Figs. 1 and 2 is 45 intended for use in a case where amputation was made below the knee and has a padded rigid annular support α adapted to fit around the stump of the leg just below the knee, provided with upwardly extending arms b , b jointed at c , c to arms d , d which carry at 50 their upper ends a padded U-shape support e adapted to be secured by hooks and a lace to the thigh above the knee. The annular support α is carried by four arms f which 55 curve inwardly and downwardly therefrom

so as to constitute a cage-like frame into which the stump extends, and they are secured at their lower ends by welding, brazing, or the like to a thin steel tube g which constitutes a peg and is pivoted at its lower 60 end in a position corresponding with the ankle of the user by a crowbolt h to a wooden foot j . A leather bucket k is secured to the annular support α and depends therefrom into the cage-like frame. The bucket k 65 is open at or toward the front and provided with hooks and a lace so that it is adjustable and may always be made to fit closely around the stump. The foot j is provided with an articulated toe portion m normally 70 maintained in extended position by blocks of soft india rubber, such as n , disposed in the gap between the toe portion m and the main portion j of the foot, said gap being covered by a strip o of leather or the 75 like. The heel and sole of the foot are padded as at p , q , with india rubber or the like to prevent jar, and in order that the foot j may be restored to its normal position after 80 flexure at the bolt h , a bifurcated link r pivoted to the peg g (or a sleeve s surrounding and secured to said peg) by a cross bolt t is pivoted to a plunger u extending into a metal lined aperture in the foot j where a spring v 85 presses upon a head w on said plunger and upon an abutment x in the foot, a pad w' of india rubber being interposed between the head w and the bottom of the aperture. In order to prevent the trouser leg from flapping loosely where the calf of the leg should 90 be, front and rear members y and z and side members 11 , 11 are respectively secured to the corresponding arms f of the cage-like frame. The front member y is also secured to the corresponding end of a cross bolt 12 , 95 which passes through the peg g , or sleeve s , and to the bifurcated link r , the rear member z is also secured to the corresponding end of the cross bolt 12 and to the peg g near the bottom thereof, while the side members 11 , 11 are secured to the sides of the 100 foot j .

The form of artificial leg illustrated in Figs. 3 to 6 of the drawings is intended for use in a case where amputation was made 105 above the knee and is of substantially the same construction, and those parts of this form of the invention which correspond with similar parts in the form just described are indicated by the same references. 110

The annular support α is adapted to fit around the stump of the thigh and is carried by four arms f , which are secured at their lower ends by brazing, welding or the like to a thin steel tube 13 which constitutes a portion of a peg. The bucket k is provided with an upward extension 14 whereof the upper edge is inclined and padded to fit into the groin and said bucket and extension 10 are each open toward the front and provided with hooks or eyelets and a lace so that they may be adjusted to always fit closely around the stump and thigh respectively. The portion 13 of the peg is connected, at a position corresponding in height with the knee joint of the user, with a thin steel tube 15, constituting another portion of the peg, by a knuckle joint 16, see Figs. 5, 7 and 8, and said portions of the peg are normally maintained in alinement by a spring 16^a within the portion 15 attached at its one end to a cross bolt 12 by an eye 16^b and at its other end to a cross bolt 17 by an eye 16^c, the bolt 17 passing through slots 17^a in the portion 15 and being secured to a sleeve 18 slidable upon said portion and adjustably attached by a chain 19 to a loop 20 formed at the bottom of one of the arms f . The portion 15 of the peg is pivotally connected at 30 its lower end, in a position corresponding with the ankle joint of the user, by a cross bolt h with a wooden foot j and the bifurcated link r is pivoted to the portion 15 of the peg (or sleeve s surrounding and secured 35 to said portion) by a cross bolt t .

In order to prevent the trouser leg from flapping loosely where the knee and the calf of the leg should be an annulus 21 is secured by its inner peripheral flange 22 to the portion 15 immediately below the knuckle joint 16 (see Fig. 5) and to the outer peripheral flange 23 of said annulus are secured front and rear members y and z and side members 45 11, 11 respectively. The side members 11, 11 are prolonged upwardly above the annulus 21 and are pivoted at 24, 24, on the same horizontal axis with the knuckle joint 16, to connecting pieces 25, 25, secured at their upper ends to the corresponding arms f , f , while the front member y is prolonged upwardly above the annulus 21 and curved about said horizontal axis as a center, as at 50 26 said upward extension 26 being slidingly engaged by a pin 27 carried by a bifurcated bracket 28 mounted at the lower end of a connecting piece 29 secured at its upper end to the front arm f .

In order to assist in maintaining the leg in alinement on the stump that arm f at the 60 outside of the leg is extended upwardly above the annular support α as at 30 and bears against or is secured to the extension 14. The bucket k and its extension 14 are sufficient to secure the artificial leg to the 65 stump, but in order to prevent accidental

displacement and to give a feeling of greater security to the wearer, further means of attachment, now to be described, may be provided.

A shoulder harness 31 adapted to be fastened, for instance by straps and buckles as at 32, is provided at or about the waist line, with a series of pulleys 33, over which passes a length of chain 34 composed of flat plate links pivoted together, (see Fig. 6) one end 70 of said chain being secured to a leather tab 35 provided at its lower end with an eyelet 36 adapted to engage a hook 37 formed at the top of the front arm f , while the other end of the chain 34 is adjustably formed as 80 an eye by looping it upon itself and passing it through a ring 38 provided with a set screw 39 as shown in Fig. 6, said eye being adapted to engage a hook 40 mounted upon a tab 41 secured to the extension 14 at the 85 rear of the latter. Further a strap 42 secured to the shoulder harness 31 is adapted to engage a button 43 or the like on the extension 14 at the outside of the leg, in order to prevent any tendency of the upper part 90 of the artificial leg to move outwardly sideways.

In a case where amputation was made through the knee joint the cage-like frame would be pivoted between a pair of arms secured at each side of and extending upwardly and outwardly from the peg, and adapted to receive the cage-like frame between them, the bottom of the cage-like frame being connected with the peg by a spring adapted normally to maintain the peg in alinement.

I claim:—

1. An artificial leg having a rigid annular support adapted to receive the stump of the leg, a tubular peg, a cage-like frame 105 connecting said rigid annular support with said tubular peg, and a bucket depending from said rigid annular support.

2. An artificial leg having an annular support adapted to receive the stump of the leg, a tubular peg divided into two portions, a knuckle joint uniting said portions, a spring connected with said portions and adapted to maintain them in alinement, a cage-like frame connecting said annular support with 115 one portion of said tubular peg, and a bucket depending from said annular support.

3. An artificial leg having an annular support adapted to receive the stump of the leg, a tubular peg divided into upper and 120 lower portions, a knuckle joint uniting said portions, a sleeve slidable on the lower portion, a spring attached to said lower portion and to said sleeve, a chain attached to the upper portion, and to said sleeve, a 125 cage-like frame connecting said annular support with said upper portion, and a bucket depending from said annular support.

4. An artificial leg having an annular 130

support adapted to receive the stump of the leg, a tubular peg, a cage-like frame connecting said annular support with said tubular peg, a bucket depending from said annular support, an artificial foot pivoted to said tubular peg, a link connected with said tubular peg, and a spring connection between said link and said foot adapted to restore said foot to its normal position after 10 flexure about its pivotal axis.

5. An artificial leg having an annular support adapted to receive the stump of the leg, a tubular peg divided into upper and lower portions, a knuckle joint, uniting said 15 portions, a spring connected with said portions and adapted to maintain them in alinement, a cage-like frame connecting said annular support with the upper portion of said tubular peg, a bucket depending from 20 said annular support, an artificial foot pivoted to the lower portion of said tubular peg, a link connected with the lower portion of said tubular peg, and a spring connection between said link and said foot 25 adapted to restore said foot to its normal position after flexure about its pivotal axis.

6. An artificial leg having an annular support adapted to receive the stump of the leg, a tubular peg, a cage-like frame connecting said annular support with said tubular peg, a bucket depending from said 30

annular support, an artificial foot pivoted to said tubular peg, a plunger in a recess in said artificial foot, a head on said plunger and an abutment in said recess, a spring 35 between said head and said abutment, a bifurcated link connected with said tubular peg and with said plunger, and a frame simulating the shape of the calf of the leg secured to said cage-like frame, substantially as set forth. 40

7. An artificial leg having a tubular peg, an artificial foot pivoted to the lower portion of said tubular peg, a plunger in a recess in said artificial foot, a head on said 45 plunger and an abutment in said recess, a spring between said head and said abutment, a bifurcated link connected with the lower portion of said tubular peg and with said plunger, a frame secured to said lower portion 50 and simulating the shape of the calf of the leg, and flexible means simulating the shape of the knee, substantially as set forth.

8. An artificial leg having an annular support, a bucket depending from said annular support, in combination with a shoulder harness provided adjacent the waistline with a series of pulleys, a chain whereof the length is adjustable passing over said pulleys and connected at its opposite ends with 55 said artificial leg. 60

FREDERICK JOHN STAVELEY BULFORD.
